Attorney.

UNITED STATES PATENT OFFICE.

JOHN FREDERICK HORSHAM, OF LAUREL HILL, NEW YORK.

THERMOSTAT.

1,418,928.

Specification of Letters Patent. Patented June 6, 1922.

Application filed October 17, 1918. Serial No. 258,664.

To all whom it may concern:

Be it known that JOHN FREDERICK HORSHAM, citizen of United States, residing at Laurel Hill, Queens County, New York, has 5 invented a new and useful Improvement in Thermostats, of which the following is a specification.

This invention relates to thermostats and it has for an object to provide a cheap and 10 inexpensive thermostat which is characterized by rapidity of action under variation in temperature, thermostats constructed according to my invention being particularly advantageous for use as fire alarms, although 15 they may be used for other purposes as well, as will be understood.

The invention has for a further object to provide a simple arrangement for the testing 20 of the operative condition of the thermostat and circuit, whether the thermostat is employed singly or as one of a string.

For further comprehension of the invention, and of the objects and advantages thereof, reference will be had to the following 25 description and accompanying drawings, and to the appended claims in which the various novel features of the invention are more particularly set forth.

Figure 1 of the drawings is a vertical section 30 view of a thermostat constructed according to my invention.

Figure 2 is a horizontal section on the line 2—2 of Figure 1.

Figure 3 is a horizontal section on the line 35 3—3 of Figure 1.

Figure 4 is a diagram of the electric circuit employed when a single thermostat is employed with the alarm.

As here shown, my improved thermostat 40 comprises a tube 1 the lower end of which is closed, and enlarged as at 2 to form a receptacle for a contact-bridging liquid 3, preferably mercury.

Extending downwardly within this tube 45 from a point about midway of its height is a second, smaller tube 5 which is open at top and bottom and has its lower end projecting into the mercury 3. The annular space between the top of this tube 5 and 50 the main tube 1 is sealed as shown at 6. The tube 1 is also preferably formed near its upper end with an enlargement 7 to provide an air chamber. These tubes 1 and 5 may be made of any suitable material. In the embodiment of the invention here shown they 55 are formed of glass.

The portion of the outer tube which extends above the inner tube is enclosed in a jacket 8 of heat-insulating material, such as asbestos to prevent the heated air coming directly in contact with the tube. The lower portion of the tube may be protected from damage, when formed of glass, by any suitable means such as the skeleton metallic structure 9. A plug 10 of any suitable material such as porcelain or plaster of Paris closes the upper end of the tube 1.

Extending downwardly through a central aperture in the plug 10, and into the tube 5, are a series of insulated wires 15, 16, and 70 17, the tips of which are bared. The wires 15 and 16 extend into the mercury 3 while the wire 17 terminates at a distance above the mercury.

In use the wires 15, 16, and 17 are connected to a suitable alarm indicator in a manner to cause an alarm to be given when an increase of temperature causes the mercury to rise in tube 5 and touch wire 17 while the thermostat may be tested by a hand 75 switch to which one of the wires extending into the mercury is connected.

In Figure 4 I have shown the wiring for a single thermostat. The wire 15 is here shown as leading to one terminal of an alarm 80 bell 20 and the wire 16 to one terminal of a normally open hand switch 21. Wire 17 leads through a battery 22 to the other terminal of the bell 20, while a wire 23 connects the battery 22 with the other terminal 85 of the hand switch 21.

It will be apparent, of course, that any desired number and character of alarm devices may be employed in lieu of, or supplementary to, the bell 20.

The operation of the thermostat as constructed according to my invention is as follows:

The lower portion of the tube 1 constitutes a closed air chamber as will be apparent. When the temperature in the vicinity of the thermostat rises this air is caused to expand. The air in the upper portion of the tube, which is protected by the heat-insulating jacket 8, remains cool and in consequence the increased pressure in the lower chamber acts on the mercury and forces it upward in the inner tube 5 until it touches the wire 17. A circuit is thus closed through the mercury, wire 17, battery 22, bell 20, and wire 15, causing 90 the alarm to sound.

If at any time it is desired to test the alarm

system, switch 21 is closed completing a circuit through wire 23 battery 22 bell 20, wire 15 and the mercury in the thermostat.

It will be apparent that I have provided 5 a thermostat characterized by great sensitivity to temperature changes and by rapidity of action as the expansion of the air in the lower chamber in the thermostat will result in a high ratio of movement of the 10 mercury in the tube 5 by reason of the small area of such tube in comparison with the total area of contact between the air and mercury.

What I claim as my invention and desire 15 to protect by Letters Patent is as follows:

1. In a thermostat, a pair of separated air chambers each of which is closed to the outer air, a contact-bridging liquid in one of said chambers, a conduit leading from the lower 20 portion of the other one of said chambers into the first mentioned chamber and having one end extending downwardly into the said liquid, electrical contact members one of which is located in the said conduit above 25 the normal level of the said liquid and a heat-insulating jacket enclosing the chamber from which said conduit leads.

2. A thermostat comprising a substantially cylindrical receptacle having an enlarged bulb at its lower end and a second 30 enlargement near its upper end, a contact-

bridging liquid in said bulb, a tube open at both ends extending downwardly in the said receptacle from a point below the said second enlargement into the said liquid, 35 means sealing the space between the upper end of said tube and the wall of the receptacle, a pair of electrical contact members in normal contact with the said liquid, a third contact member above the normal level 40 of the liquid, and a heat insulating jacket surrounding the receptacle above the said sealing means.

3. A thermostat comprising a substantially cylindrical receptacle having an enlarged bulb at its lower end and a second enlargement near its upper end, a contact-bridging liquid in the said bulb, a tube open at both ends extending downwardly in the said receptacle from a point below the said second enlargement into the said liquid, 45 means sealing the space between the upper end of said tube and the wall of the receptacle, a pair of electrical contact members in normal contact with the said liquid, and a 50 heat-insulating jacket surrounding the receptacle above the said sealing means.

In testimony whereof, JOHN FREDERICK HORSHAM has signed his name to this specification this 4th day of May, 1918.

JOHN FREDERICK HORSHAM.
